UNITED STATES PATENT OFFICE.

CHARLES W. BARNABY, OF NEW YORK, N. Y.

TYPE-WRITER.

1,302,892.

Specification of Letters Patent.

Patented May 6, 1919.

Application filed May 19, 1917. Serial No. 169,677.

To all whom it may concern:

Be it known that I, CHARLES W. BARNABY, a citizen of the United States, and resident of the borough of Richmond, county of Richmond, city and State of New York, have invented certain new and useful Improvements in Type-Writers, of which the following is a specification.

My invention relates more especially to typewriters in which compactness of form is a consideration for rendering them more conveniently transported and the primary object of this invention is to provide an improvement in the means for mounting platens in their carriages so as to occupy minimum space beyond the edges of the paper. A further object of my invention is to provide a carriage of improved construction which embodies a removable end whereby sheets of greater width than may be normally used on the carriage may be written upon over a portion of their width. My invention is herein exemplified as applied to a top strike machine but is equally applicable to front strike and other types of machines. The present application includes certain parts originally claimed in my copending application Serial No. 112,951, filed August 3rd, 1916.

In the drawings,—

Figure 1 is a longitudinal section of a carriage and platen illustrating one application of my invention;

Fig. 2 is an end elevation of the same taken from the right of Fig. 1;

Fig. 3 is a longitudinal section of a carriage and platen illustrating another application of my invention;

Fig. 4 is a transverse section through the center of the main part of the carriage, an end view of the platen, and section through handle stem and inwardly extending part of the end wall of carriage near the end of platen, the line spacing lever being removed but its pawl and pivot screw for said pawl being shown in position; all as viewed from the right of Fig. 3;

Fig. 5 is an end elevation taken from the left of Fig. 3;

Fig. 6 is a top view of a portion of the left end of Fig. 3;

Fig. 7 is an end view illustrating still another application of my invention;

Fig. 8 is a longitudinal section and,

Fig. 9 a top view of the right hand end 55 of the carriage and platen shown in Fig. 7;

Fig. 10 is a perspective view illustrating another adaptation of my invention as viewed partly from one end and the back, showing a sheet of paper inserted; 60

Fig. 11 is a back view of the right hand portion of Fig. 10 with the paper removed;

Figs. 12 and 13 are fragmentary end view and horizontal section, respectively, of another embodiment of my invention showing 65 the open end of carriage and platen.

In the embodiment of my invention shown in Figs. 1 and 2, the platen 1 is provided at one end with an internal bearing 2 and at the other end with a pivot 3. The frame 4 of 70 the carriage partly encircles the platen and is provided with an end wall 5 of minimum thickness, also a portion 6 extending inward and carrying a hub provided with an outer extension 6' and an inner extension 7. The 75 inner extension 7 constitutes a pivot for the platen bearing 2. End frames 8 and 9 are secured to frame 4, also to the bottom plate 10. Upon the outer extension 6 of the hub is pivoted the inwardly extending sleeve of 80 the line spacing lever 12. This lever carries a ratchet pawl 14 pivoted on screw 15 and engaging internal ratchet teeth 16 within the platen. This line spacing lever is provided with a thumb pad 13 by which it is 85 operated. The platen may also be rotated by means of the hand grip 11 provided with a pin 11' in the stem thereof. The pin 11' engages a slot in an inwardly extending sleeve 17 attached to bearing 2 of the platen 90 which construction permits the hand grip to be pushed inward to the position indicated by the dotted lines 11 within the pocket provided for it in the end wall 5 of the carriage. The features described in this 95 paragraph are for the most part covered in my copending application Ser. 95,612, filed May 5, 1916.

End wall 5 of the carriage and line spacing lever 12 are of approximately the same 100 minimum thickness and lie in the same plane throughout all their portions with which the edge of a sheet of paper passing to, around and from the platen could come in contact. Such part 11 of platen and carriage as extends outside of the outer plane of end wall 5 is collapsible to a position within this plane and such parts of end 105

wall and lever as extend inward from the inner plane of the end wall 5 are either well or well without the path of the edge of the sheet of paper in its passage around the 5 platen.

At the other end of the carriage attached to end frame 9 is a stand 18 carrying a bearing for platen pivot 3. As in the case of end wall 5, such part of stand 18 as the edge of 10 the paper can come in contact with is of minimum thickness and no parts of stand 18 or of the carriage or platen extend outside of the outer plane of 18. Such parts of 18 as extend inward from its inner plane, as the 15 portion which is attached to end frame 9 and the boss for bearing for platen pivot 3, are well within or well without the path of the sheet of paper.

The sheet of paper is held in contact with 20 the platen by rollers 19 and 20 provided with a pivot at each end journaled in one end of links 21, the other end of the links being pivoted to the end frames 8 and 9, the rollers being forced against the platen 25 by the action of spring 22 (see Fig. 4). The paper is also held in contact with the platen by a small roller 23 at each end of the platen and also by a clip plate 24 (see Fig. 10) which is preferably graduated 30 along its edge adjacent to the writing line.

With this construction I am able to mount a platen pivoted at both ends in a carriage with closed ends which will receive, with comfortable clearance, letter paper of the 35 usual width of eight to eight and one half inches and at the same time not exceed an overall length of nine inches for the carriage, platen and attachments, which dimension I find to be about the minimum for the 40 width of a main frame that will house a standard keyboard with shift and back space keys.

The embodiment of my invention shown in Figs. 3, 4, 5, and 6 employs many of the 45 features of the embodiment just described but differs from same in several features. The ratchet teeth 16 are in this case notched into the end face of the platen rim, instead of being located on the interior face of same. 50 The ratchet pawl 14 is pivoted on a radially disposed pivot 15, the pawl and pivot screw being placed sufficiently below the periphery of the platen to avoid interference with the margin 25 of the sheet of paper which may 55 extend beyond the end of the platen. The hub 7 upon which the right hand end of the platen is pivoted is extended well to the left end of the platen where it is chambered to act as a supporting bearing for 60 pivot 26 extending inward from the left end of the platen. This construction supports the outer end of the platen with sufficient rigidity for ordinary writing purposes but without too heavy and cumbersome construction this overhung platen

might not maintain its alinement under all shocks of transportation or abnormal accidental stress when in service. I therefore prefer to employ an auxiliary pivot 30 supported by a removable standard 29 which 70 is shown hinged at 31 so that it may be dropped to the dotted position 29'. It is intended that this end pivot 30 shall remain, normally, in engagement, as, by the employment of my invention which gives a minimum extension of the carriage beyond the 75 margins of the sheet of paper which it will receive, a carriage of nine inches or less overall length will receive all sizes of paper and envelops ordinarily written upon. In 80 Fig. 4 a sheet of paper is shown passed around the platen, one end at 32 and the emerging end at 33. In Fig. 3 the width of the paper is seen extending from one edge 25 to the other 34, the whole space 85 between the inner surface of walls 5 and 29 being available for the passage of the paper. When it is desired to write upon a long envelop or other article the end bearing is dropped to the position 29', 30', when 90 the article can extend any distance beyond the end of the platen and carriage as indicated by the broken lines 35. The keeper 27 engaging the groove 28 maintains the platen in a fixed endwise position when end pivot 95 30 is out of engagement.

The bar 36, Figs. 3, 5 and 6, holds the auxiliary pivot in engagement. Bar 36 is pivoted on an enlarged portion of pivot screw 30. The bar has recesses near each 100 end which engage circular grooves in the ends of studs 37. When the bar is swung on the pivot 30 to the dotted position 36' the recesses are thrown out of engagement with studs 37 and the bearing is free to 105 drop to the position 29', 30'.

Figs. 7, 8 and 9 illustrate my preferred method of applying a peripheral toothed ratchet wheel to my invention. The end wall 5 and part of the inward extension 6 110 is cut away from 42 to 43 to give clearance for the line spacing lever 12. This lever is normally held in the position shown by the action of the lever, which is partly broken away to show part of it, on screw 15. In 115 this normal position the tail 40 of the pawl is in contact with end 43 of the cut out portion of the inner extension 6, thereby holding the engaging end of pawl 14 out of engagement with ratchet teeth 16. A jaw of 120 the spring detent 41 engages one of the ratchet teeth depressions to maintain the platen in proper position. When line spacing lever 12 is pressed backward the pressure is removed from tail 40 of the pawl 125 and its engagement end 14 drops into engagement with a ratchet tooth 16. Upon pressing thumb pad 13 backward to the dotted position 13' the engaged pawl is carried to 14'. The periphery of ratchet teeth 16 130

is kept below the periphery of platen 1. The body of the spring detent 41 is also kept below the periphery of the platen. The jaw of the detent, also pawl 14 and its 5 spring 38 and spring engaging pin 39 may extend or operate to points outside of the periphery of the platen, providing they are at all times within the space between where the paper leads on to the platen from 32 and 10 where it leads off from the platen to 33. When these elements are thus placed the margin 25 of the paper may extend under and over them without obstruction until it 15 comes in contact with the inner face of wall 5 and lever 12, as indicated at 25, Fig. 8.

In the embodiment of my invention illustrated in Figs. 10 and 11 the outer end 45 of platen is supported by an arm 48 rigidly attached to end frame 5. The outer end of 20 this arm carries rigid bracket 47 which is provided with a bearing boss 46 in which outer platen pivot 3 is journaled. The other end of the platen is journaled on a hub extending inside the end of the platen from 25 the end wall 5 of the carriage. The construction is similar to that shown in Fig. 1 except that outer pivot 3, instead of being supported from end frame 9 by standard 18, is supported from frame 5 by means of 30 an arm extending the whole length of the platen. Fig. 10 differs from Fig. 3 in that, though in both cases the outer end of the platen has a supporting means extending from end wall 5 of the carriage, in Fig. 10 35 this supporting means 48 is carried entirely outside of the platen while in Fig. 3 it is wholly inside the platen. In the Fig. 10 embodiment, as is the case with the Fig. 3 embodiment when the end standard 29 is 40 dropped to the 29' position, the end of the carriage is entirely open so that there is nothing to interfere with the paper extending 45 as far outside of the end of the carriage as desired, as is illustrated in Fig. 10 in which the sheet of paper passes from 32 under and around the platen, emerging from the top to 33. Margin 35 of the paper, it will be noted, extends entirely outside of 50 the end of the carriage and pivot arm 48 is entirely clear of the path of the paper, and in no manner interferes with the passing to, around and from the platen or beyond 55 the end of platen and carriage.

As in the case of Fig. 3 I prefer, in the 55 Figs. 10 and 11 embodiment, to employ a disengaging end support 49 pivoted at 50, 50' and provided with holes 51' to engage pins 51 in bearing bracket 47. Fig. 11 shows the end support in engagement at 49' 60 and out of engagement at 49. A latch 52, Fig. 10, provided with a jaw 53, engages the edge of support 49 when the latter is thrown into engagement with end bracket 47 to maintain the latter in engagement.

65 Figs. 12 and 13 illustrate another appli-

cation of my invention, the removable end standard 57 in this embodiment being hinged to platen pivot bearing 55 and foldable to a position entirely within an extension of the peripheral surface of the platen, 70 instead of being hinged to the end of carriage and foldable to a position outside of an extension of said peripheral surface. Bearing piece 55 is mounted on platen pivot 3 and to this bearing piece is hinged, on 75 pin 31, the bearing standard 57. The dotted lines 57' show this standard in platen supporting engagement, in which position holes 56' in standard 57 engage pins 56 in end frame 54 of carriage. 80

Obviously, various modifications in the construction herein shown and described, could be embodied within the scope of my invention, so that I do not wish to be limited to the specific construction shown and described. 85

I claim:

1. In a typewriter, the combination with a platen journaled at one end and supported from said journaled end, of a movably mounted journaling support movable into and out of journaling support with the other end of said platen, said journaling support when out of journal supporting position being so arranged as to lie entirely 95 clear of a longitudinal extension of the periphery of said platen.

2. In a typewriter, the combination with a reciprocable carriage, of an elongated sleeve rigidly connected at one end to said carriage, a platen journaled on said sleeve, and a pivot movable into and out of journaling engagement with the other end of said platen, said pivot when out of journaling engagement being adapted to lie 105 clear of a longitudinal extension of the peripheral surface of said platen.

3. In a typewriter, the combination with a reciprocable carriage, of an elongated sleeve rigidly connected at one end to said carriage, a platen journaled on said sleeve, and a pivot movable into and out of journaling engagement with the other end of said platen, said pivot being hinged to said carriage and adapted in its position away 110 from said platen to lie outside of a longitudinal extension of the peripheral surface of said platen. 115

4. In a typewriter, the combination with a platen, journaled at one end, of a journaling support movable into and out of supporting engagement with the other end of said platen, said journaling support when out of supporting engagement being arranged to lie entirely clear of a longitudinal 120 extension of the periphery of said platen. 125

5. In a typewriter, the combination with a reciprocable carriage, of a platen journaled at one end in said carriage, and a pivot movable into and out of journaling 130

- engagement with the other end of said platen, said pivot when out of journaling engagement being adapted to lie entirely clear of a longitudinal extension of the 5 peripheral surface of said platen.
6. In a typewriter, the combination with a reciprocable carriage, of a platen journaled at one end in said carriage, and a pivot movable into and out of journaling engagement with the other end of said platen, said pivot being hinged to said carriage and adapted in its position away from said platen, to lie outside of a longitudinal extension of the peripheral surface of said 10 platen.
7. In a typewriter, the combination with an open end reciprocable carriage, of a platen journaled in said carriage, and a disengageable auxiliary pivot support for said 15 platen at the open end of said carriage, said pivot support when out of engagement being in a position clear of a prolongation of the periphery of said platen.
8. In a typewriter, the combination with an open end reciprocable carriage, of a platen supported and controlled independently of supporting means at the open end of the carriage, and an auxiliary supporting means for said platen adapted to be 20 placed in and out of supporting engagement at the open end of said carriage and so arranged that when out of supporting engagement, said supporting means will be entirely clear of the path of a sheet of 25 paper passed about said platen and extending beyond the open end of said carriage and said platen supporting means.
9. In a typewriter, the combination with an open end carriage, of a platen rotatably 30 mounted in said carriage, and a movable bracket adapted to close the open end of said carriage and pivotally support the end of said platen from said carriage.
10. In a typewriter, the combination with an open end carriage, of a platen rotatably 35 mounted in said carriage, and a hinged supporting means adapted to bridge said open end of said carriage and pivotally support said platen from said carriage.
11. In a typewriter, the combination with an open end carriage, of a platen rotatably 40 mounted in said carriage, and a hinged supporting means pivoted to said platen, axially, and foldable against the end of said platen within a space which would be 45 included within an extension of the periphery of said platen, said supporting means being adapted through its hinged construction to be swung across the opening at the end of said carriage and engage the end of 50 said carriage to pivotally support said platen.
12. In a typewriter, the combination with an open end carriage, of a platen rotatable 55 in said carriage, and a platen support hinged to the end of said carriage and adapted to be swung across the open space 60 between the ends of said carriage and said platen and axially engage and support said platen.
13. In a typewriter, a carriage, a platen means for operably supporting said platen entirely from one end of said carriage, and an auxiliary supporting means movable into and out of operating engagement with the 65 other end of said platen for providing at 70 will additional platen supporting means at the other end of said carriage.
14. In a typewriter, a carriage, a platen rotatably supported from one end of said carriage, and means movable into and out of position to rotatably support the other end of said platen, said carriage being provided with an open end adapted to be closed by said movable platen supporting means 75 when in position to rotatably support said platen.

CHARLES W. BARNABY.
